The ornamental design for a golf club head, as shown and described.

DESCRIPTION

FIG. 1 is a front elevational view of a golf club head embodying the inventive design.

FIG. 2 is top plan view thereof.

FIG. 3 is a heel-side elevational view thereof.

FIG. 4 is a toe-side elevational view thereof.

FIG. 5 is a bottom plan view thereof.

FIG. 6 is a rear elevational view thereof; and,

FIG. 7 is a top perspective view thereof.

The score lines and the face of the club are flush at the front surface.

The shading represents two different surface treatments. The broken lines immediately adjacent the shaded areas represent the bounds of the claimed design, while all other broken lines are directed to environment and are for illustrative purposes only; the broken lines form no part of the claimed design.
